UNITED STATES PATENT OFFICE.

ARTHUR J. MILNE SMITH, OF SYDENHAM, ENGLAND, ASSIGNOR OF THREE-FOURTHS
TO THE SANRAINE SYNDICATE LIMITED, OF LONDON, ENGLAND.

CARDING OF KAPOK AND LIKE FIBER AND THE PRODUCTION OF A FLEECE THEREFROM.

1,177,903.

Specification of Letters Patent.

Patented Apr. 4, 1916.

Application filed August 24, 1915. Serial No. 47,198.

To all whom it may concern:

Be it known that I, ARTHUR JAMES MILNE SMITH, a subject of the King of Great Britain, residing at 210 Venner road, Sydenham, in the county of Surrey, England, have invented new and useful Improvements in and Connected with the Carding of Kapok and like Fiber and the Production of a Fleece Therefrom, of which the following

is a specification.

The production of fleece from kapok and like fiber presents difficulties in effecting a smooth layer of uniform depth on the teeth of the wire card of the carding cylinder or drum and in the removal of such layer when deposited thereon, which it is the object of the present invention to avoid.

According to my invention I propose to effect the removal of the fleece from the bent teeth of the wire card of the carding cylinder or drum by a reverse movement of such cylinder or drum to that which has been imparted thereto in effecting the deposit or collection of the layer of the fiber thereon, and which so naturally facilitates the disengagement of such layer of fiber from said bent teeth. I further prior to the deposit of the layer of fiber upon the teeth of the wire card of the carding cylinder preferably apply to such cylinder either wires or fine open material through which such teeth project and which constitute a backing above which the fibers are deposited, and by subsequently drawing off which backing the formed fleece will be stripped from said cylinder on the reverse movement thereof. The backing may remain as a permanent attachment to the fleece, in which case it will preferably consist of fine, open, gauze or muslin or similar fabric, or even of fine paper, so that it may be cut up or shaped with the fleece to the form in which it is required to be used, and will prevent such fleece breaking up or tearing during its manipulation or in transport. Or the fleece may be detached from the wires or fabric constituting the backing by which it has been stripped from the carding cylinder, and if necessary placed upon any other suitable backing or between layers of suitable material applied to its opposite surfaces. Or again one or both surfaces of the fleece after the removal from the wires or backing might be suitably treated, (such as by a suitable mucilage or the like) to produce a film con-

necting the fibers in a manner to oppose the breaking up or tearing apart of the fleece in handling or during the transport. The fibers taken up by the teeth of the carding cylinder in its rotation are brought into contact with the teeth of a length of wire card one end of which is held stationary while the other end is free and follows the contour of the periphery of the drum in its operative direction of rotation, and which bears thereon so that its teeth effects the uniform spreading out of such fiber and produces the required smooth fleece of the required thickness.

An apparatus constructed in a suitable manner for carrying my invention into effect is illustrated in the accompanying drawing, in which—

Figure 1 is a side elevation of such apparatus, and Fig. 2 a vertical section thereof, but with the frame omitted.

In this apparatus 1 is a carding cylinder suitably mounted upon and actuated to rotate in a frame 2, such cylinder being clothed with ordinary wire cards 3 having bent teeth. A length of card 4 is also suitably supported on the frame 2 in such a position that its free end follows the contour of the periphery of cylinder 1 against the teeth of the card 3 of which the teeth of said card 4 bear. The kapok or other fiber to be formed into a fleece is treated on cylinder 1 in the manner to be hereinafter described, but before feeding such fiber thereto I cause a length of suitable material to be rolled around the periphery of said cylinder with an allowance for a slight overlap. If the fleece is required to be provided with a permanent backing this material may consist of open gauze or coarse muslin, or even thin paper, which the teeth of the wire card 3 will readily penetrate and project beyond. If the backing of the fleece is to be removed therefrom when stripped from the carding cylinder a series of wires or wire gauze might be employed and be similarly applied to the cylinder 1 so that the teeth thereof project beyond same.

In the case of the employment of a backing of fabric or paper a roll 5 of same may be mounted on frame 2, and the hinged part 7 of the cylinder casing having been first turned back, the end of such fabric or paper will be hooked on to the teeth of the wire card 3 of the cylinder 1 at any suitable point,

so that the rotation of such cylinder will draw off the fabric or paper and cause the teeth of card 3 to readily penetrate through such backing which passes to the root of the 5 teeth as the fabric or paper is applied to the periphery of the cylinder. The action may be assisted if necessary by an auxiliary roll 6 also provided with a card surface the teeth of which intermesh with those of the 10 card 3 of cylinder 1 and between which roll and cylinder the fabric or paper passes. The part 7^x of the casing 7 inclosing the cylinder 1 is hinged to permit of the roll 6 being applied to the cylinder, after the part 7^x has 15 been opened, so that the teeth of the card on the roll 6 and those 3 of the cylinder 1 intermesh, the roll 6 being removed and the part 7^x of the casing closed when the length of fabric has been applied around the periphery 20 of such cylinder and severed from the length on the roll 5 thereof. The cylinder 1 thus fitted with the fabric or paper and the teeth of its carding surface 3 projecting therethrough is then rotated in the required direction 25 to allow the teeth to take up a small quantity of the fiber which is fed thereto in any desired manner, such as by grooved rollers 8 taking their supply from a traveling band 9 upon which the fiber is deposited. 30 The fiber taken up by the teeth of card 3 from the rollers 8 will be conveyed thereby and brought successively under the action of the teeth of the length of card 4 supported so that one end thereof is firmly held 35 in a stationary position on frame 2 while its free end follows the contour of the periphery of the drum 1 in the direction of its rotation. The teeth of this length of card 4 are also bent, the bend being situated in 40 the same direction as that of the teeth of the card 3 of the drum or cylinder 1, whereby the upper bent portions of the two sets of teeth 3 and 4 co-acting will insure the even distribution and overlapping of the successive 45 portions of the fiber conveyed by the drum 1 upon the teeth of the card of the latter, the rotation of which is continued until the necessary quantity of fiber has accumulated on the drum to constitute the fleece of the thickness required. The elastic or yielding nature of the card backing will insure the part of the length of card 4 which is free to move in relation to the drum to bear upon the fiber brought to the action of its teeth by those of drum 1 with sufficient pressure to produce the desired even spreading out of such fiber and to apply it above the upper surface of the backing 5 which has been previously placed on the periphery of such drum as already described, and to which the backing will constitute a support to enable its removal from the cylinder. The length of card 4 is mounted so as to be 50 capable of adjustment in any direction in relation to cylinder 1.

When the carding operation has been completed by the drum 1 having taken up the quantity of fiber necessary to form a fleece of the required thickness, the rotation of the drum is arrested and the overlapping portion of the backing 5 is seized and drawn out free of the teeth of card 3. The drum 1 is then left free to rotate or to be rotated in the opposite direction to that previously imparted thereto, and the length of fleece 75 pulled by its backing 5 in the direction to strip it from the periphery of the drum 1, the open nature of the backing readily permitting of such removal from the teeth of the card 3 thereon without offering such opposition as to disturb the adherence of the fiber which has been applied thereto. 80

The layer or fleece of fiber will be found to be applied to the backing in a manner which will permit of the handling thereof 85 for packing and transport, and its subsequent manipulation to reduce it to the required shape or size for use without interfering with either the continuity or thickness of such layer. 90

The fleece might however be removed from the backing by which it has been stripped from the carding cylinder and if desired applied to or between other material with which it is required to employ same, or for 95 permitting the handling or transmission thereof without risk of breaking up or tearing same. In this case the backing may as hereinbefore set forth consist of wire gauze or even of a series of wires wound around 100 the carding cylinder between the teeth of the wire card thereon and by drawing on one end of which wire cloth, or one set of ends of which wires, the completed fleece will be stripped from the cylinder as it rotates in the direction opposed to that in which the fleece has been built up thereon, after which the fleece may be removed from 105 said wire gauze or series of wires and placed upon or interposed between a layer or layers 110 of any other desired material.

What I claim as my invention, and desire to secure by Letters Patent, is:—

1. In a carding machine the combination of a carding cylinder and a length of wire 115 card secured at one end and having a free movable end following the periphery of such cylinder in the direction of its rotation, and against the teeth of the card of which cylinder the teeth of the free end of the length of 120 card bear with a yielding action, substantially as specified.

2. A method of making a kapok bat consisting of applying a web to the carding means, thereafter applying the kapok to the 125 said carding means, carding the kapok and withdrawing the web with the kapok thereon.

3. A method of stripping a carding cylinder consisting of applying a web of wire 130

to said carding cylinder previous to the application of the material to be carded, and, after carding said material, of withdrawing said wire web with the carding material thereon, and thereafter removing said material from said web.

In testimony whereof I have signed my

name to this specification in the presence of two subscribing witnesses.

A. J. MILNE SMITH.
